[57] CLAIM

The ornamental design for a barrow for use in going shopping and loading luggage, as shown and described.

DESCRIPTION

FIG. 1 is a front and top perspective view of a barrow for use in going shopping and loading luggage showing my new design;

FIG. 2 is a front elevational view thereof;

FIG. 3 is a rear elevational view thereof;

FIG. 4 is a left side elevational view thereof, the opposite side view being a mirror image of that shown;

FIG. 5 is a top plan view thereof;

FIG. 6 is a bottom plan view thereof; and,

FIG. 7 is the perspective view of this design being operated.

FIG. 1

FIG.2
